UNITED STATES PATENT OFFICE.

MORRIS F. FINKELSTEIN, OF NEW YORK, N. Y.

TAP-CONNECTOR FOR ELECTRIC CONDUCTORS.

1,266,440.

Specification of Letters Patent. Patented May 14, 1918.

Application filed May 22, 1917. Serial No. 170,170.

To all whom it may concern:

Be it known that I, MORRIS F. FINKELSTEIN, a citizen of the United States, and a resident of the city of New York, borough 6 of the Bronx, in the county of the Bronx and State of New York, have invented a new and Improved Tap-Connector for Electric Conductors, of which the following is a full, clear, and exact description.

10 This invention relates to a connector of that type whereby a branch wire or conductor can be electrically connected with a cable or main conductor.

15 The invention has for its general objects to improve the construction and operation of devices of this character so as to be reliable and efficient in use, comparatively simple and inexpensive to manufacture, and so designed that electrical connection can be 20 easily and quickly made.

A more specific object of the invention is the provision of a novel means for binding the connector to the cable in a simple, reliable and effective manner.

25 A further object is the provision of an improved clip or clamp arranged within the body of the connector and adapted to receive the end of the branch wire which is securely held by the clamping screw which 30 binds the clamp or clip on the said wire.

With such objects in view, and others which will appear as the description proceeds, the invention comprises various novel features of construction and arrangement 35 of parts which will be set forth with particularity in the following description and claims appended hereto.

40 In the accompanying drawings, which illustrate one embodiment of the invention and wherein similar characters of reference indicate corresponding parts in all the views,

Figure 1 is a longitudinal section of the connector in use;

45 Fig. 2 is a transverse section on the line 2—2, Fig. 1;

Fig. 3 is a perspective view of the clip removed.

Referring to the drawing, A designates a 50 main wire or cable, B a branch wire or cap, and C the connector.

The cable A has a portion of its insulation 1 removed at 2, so that the connector can be bound to the wires of the cable and

electrically connect therewith. The branch 55 wire B has its end 3 bared of insulation and clamped in the connector C.

The connector C comprises a tubular body 4 of steel or other metal, the ends of the tube being open. In the tube is a clip or clamp 60 5 made of a strip of brass or other metal and doubled to form a spring member 6 which lies over the body member 7. This clamp is held in place by being extended into a base member 8 which is doubled back- 65 wardly so as to lie outside the tubular body 4. The members 7 and 8 engage the same 70 wall of the body but the inner and outer surfaces respectively, and the extremity of the base member 8 is bent perpendicularly 75 into a lug 9 which engages in and closes one end of the body 4. The mouth 10 of the clamp or clip faces in the direction of the open end of the body 4 so that the branch wire 3 can be inserted in the open 80 end of the connector body and be engaged between the clamp members 6 and 7. The base member 8 is bound directly against the strands of the cable, so that a good electrical 85 connection will be obtained between the cable and the branch wire. The branch wire is securely clamped by means of a set-screw 11 which is threaded in an opening 12 in the body 4, the inner end of the screw bearing on the member 6 so as to move the same to- 90 ward the member 7 and thereby clamp the branch wire between such members. In this manner the branch wire can be easily and quickly connected or disconnected, it being merely necessary to tighten or loosen the screw 11.

The connector is bound to the cable by means of a plurality of bands 13 which pass around the cable and the body 4, as clearly shown in Fig. 1, the ends 14 of each band 95 being overlapped so that the apertures 15 in the said ends will register and engage with a stud 16 formed by reducing the outer end of the screw 17, which engages in the tapped opening 18 of the body 4. By turning the screws 17 inwardly the bands 13 can be loosened so that their ends can be disengaged from the studs 16 for removing the connector from the cable. In applying the connector to the cable the bands are 100 wrapped around the cable and body of the connector, and after the ends of the bands are engaged with the studs 16 of the screws 105

17, the screws are turned in a direction to work them outwardly so as to thereby tighten the bands and clamp the connector to the conductor.

5 From the foregoing description taken in connection with the accompanying drawings, the advantages of the construction and method of operation will be readily understood by those skilled in the art to which 10 the invention appertains, and while I have described the principle of operation, together with the device which I now consider to be the best embodiment thereof, I desire to have it understood that the device 15 shown is merely illustrative and that such changes may be made when desired as fall within the scope of the appended claims.

Having thus described my invention, I claim as new and desire to secure by Letters 20 Patent:

1. The combination of a main wire, a branch wire and a connector for uniting the wires, said connector including a body, a screw threaded therein and formed with a stud 25 on its other end, and a binding member extending around the main wire and body with its ends overlapping and having openings in its ends to engage the stud of the screw, whereby the turning of the latter in one direction loosens the band and in the other direction tightens the same.

2. The combination of a main wire, a branch wire and a connector uniting the wires, said connector including a tubular body, a clamp therein including a yielding member extending lengthwise of the said body and with which the branch wire is engaged, and a screw in the body bearing on the yielding member for jamming the same 30 into contact with the branch wire.

3. The combination of a main wire, a branch wire and a connector uniting the wires, said connector including a tubular body, a clamp therein including a yielding member extending lengthwise of the said 35 body and with which the branch wire is engaged, and a screw in the body bearing on the yielding member for jamming the same into contact with the branch wire, said clamp 40 having a member extending out of the body

and lying between and in contact with the main wire and said body.

4. The combination of a main wire, a branch wire and a connector uniting the wires, said connector including a tubular body, a clamp therein including a yielding member with which the branch wire is engaged, and a screw in the body bearing on the yielding member for jamming the same 55 into contact with the branch wire, said clamp having a member extending out of the body and lying between and in contact with the main wire and said body, the extremity of the said member being bent outwardly to engage the end of the body opposite from 60 that into which the branch wire extends.

5. A connector of the class described comprising a tubular body, a clamp formed with a doubled extremity lying within the body and having a portion extending outside the 70 body and longitudinally thereof, and a device adjustably mounted on the body and engaging the said doubled portion for clamping the same to a wire.

6. A connector of the class described comprising a tubular body having one wall provided with a plurality of threaded openings, a clamp in the body for receiving a branch wire, a screw engaging in one opening and adapted to screw inwardly to tighten the 75 clip to the branch wire, bands for binding the body to a main wire, and screws engaging in the other openings and engaging with the bands and adapted to screw outwardly 80 for tightening the bands.

7. A connector of the class described comprising a tubular body having one wall provided with a plurality of threaded openings, a clamp in the body for receiving a branch wire, a screw engaging in one opening and 85 adapted to screw inwardly to tighten the clamp to the branch wire, bands for binding the body to a main wire, and screws engaging in the other openings and engaging with the bands and adapted to screw outwardly 90 for tightening the bands, said clamp having a member lying outside the body and adapted to be clamped between the same and the main wire by the bands.

MORRIS F. FINKELSTEIN.
